[57] CLAIM

The ornamental design for a combined video tape recorder and television, as shown and described.

DESCRIPTION

FIG. 1 is a top, front and right side perspective view of a combined video tape recorder and television showing our new design, with the display screen extended and the antenna and handle in a raised position;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof.
